TWISTING SPINDLE TENSION DEVICE

Ralph H. Carter, Johnson City, and Chadwick B. Kingsbury, Elizabethton, Tenn., assignors to North American Rayon Corporation, New York, N. Y., a corporation of Delaware

Application May 20, 1949, Serial No. 94,376

6 Claims. (Cl. 242—150)

1

This invention relates to twisting spindles and more particularly spindles of the kind adapted to impart two twists to the yarn or thread undergoing twisting, for each revolution of the spindle.

The invention is a carrying forward and further development of the tensioning device used on the type of double twist spindle disclosed in the co-pending application of Chadwick B. Kingsbury, Serial No. 793,003, filed December 20, 1947, now Patent No. 2,478,926 dated January 3, 1950.

In spindles of this type, yarn, withdrawn over-end from a supply package, relatively stationary with respect to a rotating hollow spindle, passes through the tensioning device, down through the hollow spindle, emerges from a port in the spindle rotor, and then passes outwardly and upwardly around the package in the form of a so-called "free balloon," and thence to a suitable take-up device.

In the operation of such twisting spindles proper tension must be applied to the yarn at suitable points in its path of travel. In the case of spindles of the type disclosed in the aforesaid application, a yarn-tensioning system is incorporated in the upper portion of the spindle assembly. The yarn passes between the surface of a light-weight freely movable disk and the cooperating surface of its stationary supporting member, and is subjected to tension by virtue of the pressure exerted by the disk thereon. The disk is made of magnetically responsive material and the amount of pressure exerted thereby, in addition to that produced by its own weight, is controlled by a magnet disposed interiorly of the spindle assembly and immediately below the member, the pull of the magnet on the disk being adjusted by suitably spacing the magnet therefrom as by inserting non-magnetic shims.

In the tensioning device described in the aforesaid copending application, the disk must be entirely removed during the threading-up of the spindle in order to permit passage of the threading-up wire through the thread passage hole in the lower member. The disk must then be manually replaced in its operating position. This operation generally requires the use of one hand for removing the disk and the other hand for inserting the threading-up wire. During this operation the disks are often inadvertently dropped and become lost or damaged. Also, but to a lesser extent, the disks are sometimes thrown off the spindle by the action of the thread while the spindle is in operation.

It is an object of the present invention to incorporate the disk as a non-removable part of

2

the tensioning mechanism by confining it loosely in a sleeve-like cage.

A further object is to provide means whereby the disk can be temporarily tilted by the threading-up wire sufficiently to permit its passage without necessitating complete removal of the disk from the assembly.

Another object is to provide means for insuring that the disk automatically resumes its proper operating position upon withdrawal of the threading-up wire.

A still further object is to provide means for effecting automatic and momentary release of tension during the operation of the spindle in the event of jerks or plucks occurring as the thread leaves the supply package.

Other objects and advantages of the invention will be manifest from the following detailed description when considered in connection with the accompanying drawing, wherein:

Fig. 1 is a side elevation of a double twist spindle showing the cage in its upper or threading-up position, with the disk tilted and the threading-up wire in threading-up position.

Fig. 2 is a cross section of the tensioning assembly showing the cage and disk in running or operating position.

Fig. 3 is a cross section on enlarged scale of the top portion of Fig. 1.

Fig. 4 is a disassembled cross sectional view showing the sleeve-like cage, disk, and the lower tensioning member upon which the disk reposes during operation.

Referring to the drawings in detail, the numeral 1 generally designates a double twist spindle of the type disclosed in the copending application aforesaid, the same being pivotally carried by an arm 2. The spindle is driven by contact of belt 3 with whorl 4, an idler pulley 5 being used to position the belt 3. A brake device 6 is diagrammatically indicated and is used for stopping the rotation of the spindle. Yarn, drawn from a package 7 is to be pulled down through the hollow center of the spindle and out through a port in the rotor 8. This is effected by passing a threading-up wire, preferably of coil-spring type 9, through a port in the rotor 8, thence upwardly through the axial thread passage in the spindle, through the hole 23 in the insert 18 of the lower tensioning member 17, past the tension disk 10, through the opening in the top of the cage 11, until the wire projects slightly above the top of the cage.

The thread or yarn 12 from the package 7 is then looped around or attached to the thread-

ing-up wire 9 as shown in Figs. 1 and 3. The threading-up wire is then withdrawn, carrying the attached thread 12 with it, the latter being thereupon attached to the take-up spool (not shown).

During this insertion of the threading-up wire 9, the latter tilts the tensioning disk 10 as shown in Figs. 1 and 3. The cage 11 which is arranged to slide freely axially of the tensioning assembly, in turn is raised by the disk as the latter is being tilted by the threading-up wire, the upward movement of the cage being limited by means of inwardly-bent portions 13 of the lower extremity 14 of the cage. As shown, the cage is slotted laterally as at 15 for convenience in assembly. The top opening of the cage 11 is circular and of slightly less diameter than the round disk 10 so as to permit the disk to protrude partly, in tilted position, while preventing its complete emergence, as shown in Fig. 3.

The upward movement of the cage 10 is restricted by the engagement of the inwardly bent sections 13 with the lower shoulder 24 of the tensioning member 11 so that the disk cannot assume a completely vertical position with respect to its normal operating position. Thus the disk 10 cannot be inadvertently turned over, and by action of gravity the cage and disk automatically drop back to normal operating position when the threading-up wire 9 is removed.

The disk is provided with a centrally located stem 29 which may be formed integrally out of the body and which is somewhat smaller in diameter than the cooperating hole 23 in insert 18, the contour of the stem being rounded and serving to locate the disk during its return, after threading-up, to operating position and to maintain its position during normal operation. The stem also serves to prevent the disk making radial contact between its edge 26 and the inside surface of sleeve 11.

A shoulder 16 on cage 11 is provided for longitudinally spacing the cage properly in relation to the disk when the latter is in operating position and thus allow the disk to be free to respond to slight variations in the yarn and also to allow the disk to perform its nutational functions, said nutational functions being described in the aforesaid copending application. The cage, when in lower or operating position (Fig. 2), confines the disk entirely in its operating position. While a slidably disposed cage is preferred, a cage permanently fixed in its extended position could be used. Also, if suitable threading-up means were available, the cage could be fixed in its down or operating position.

Automatic release of tension is accomplished by virtue of the S-shaped path which the thread pursues in its passage through the assembly, more particularly as follows: The thread 12 passes from the package 7 over lip 25 of cage 11, thence around the rounded edge 26 of disk 10, approaching both members throughout an arc of 360°, thence between the tension surfaces of disk 10 and insert 18 and downwardly through hole 23 in insert 18. It is apparent that increased tension tends to cause the thread 12 to assume a more direct path through the assembly which in turn causes disk 10 to be lifted from insert 18, thus releasing the pressure on thread 12 at point 27 (Fig. 2). It is also apparent from the foregoing that the thread continually wipes the lip of the sleeve as well as the tensioning surfaces, in the manner described in the aforesaid co-pending application.

A still further feature of the invention resides

in providing a hard, wear-resistant surface on the member 17 against which the disk 10 bears. In the preferred embodiment the member 17 is constituted of non-magnetic material such as a suitable stainless steel with a wafer-like insert 18 of glass, ceramic, or other hard wear-resistant material having non-magnetic properties. A preferred material suitable for constituting the wafer is the ceramic composition described in U. S. Patent No. 2,214,703.

The purpose of this insert is to prevent scratching or otherwise marring of the aperture through which the thread passes and which passage may become scratched by any burr present on the threading-up wire and cause damage to the thread. The insert 18 is retained in a recess in the member 17 as by cementing or otherwise.

The arrangement of the magnet and the means for adjusting its pull on the disk constitute no

part of the present invention, being adequately described in the aforesaid copending application. However, by way of brief explanation, reference is directed to Fig. 2, where 19 designates the magnet, 10 the disk attracted by the magnet and 20 the shims used for adjusting the pull of the magnet on the disk, a suitable bushing 21 being provided for guiding the threading-up wire through the aperture in the member 18. A spring 22 serves to hold the magnet in position. A recess or socket 23 is provided in member 17 for insertion of a spanner wrench or the like during assembly.

Modification of this invention will be readily recognized in the art and it is desired to include all modifications coming within the scope of the appended claims.

We claim:

1. In a twisting spindle including a device for tensioning thread comprising, in combination, a flat surface having a thread opening therein, a round disk having a short stem projecting into said opening and fitting loosely therein and having a marginal flange extending away from said flat surface, said disk and said surface normally lying in contact but being susceptible of relative nutation during passage of thread therebetween and through the opening beside said stem, and a cage confining said disk while permitting its nutational tension-exerting movement, said cage having an uninterrupted circular opening of sufficient diameter to permit tilting and partial emergence of said disk therefrom but of insufficient diameter to allow complete removal of said disk and insufficient vertical depth to permit the turning over of said disk in said cage, said opening in said cage permitting unhindered approach of the thread to said disk throughout an arc of 360°.

2. In a twisting spindle including a device for tensioning thread comprising, in combination, a flat surface having a thread opening therein, a circular disk having a short stem projecting loosely into said opening and having a marginal flange extending away from said flat surface, said disk and said surface normally lying in contact but being susceptible of relative nutation during passage of thread therebetween said through the opening beside said stem and a cage for confining said disk while permitting its nutational tension-exerting movement but limiting other movement thereof beyond a predetermined extent, said cage having an uninterrupted circular opening of a diameter less than the diameter of said disk for preventing complete removal of said disk from said cage and insufficient vertical depth to permit the turning over of said disk in said cage.

3. In a twisting spindle including a device for tensioning thread comprising, in combination, a flat surface having a thread opening therein, a round disk having a short stem projecting into said opening and fitting loosely therein and having a marginal flange extending away from said flat surface, said disk and said surface normally lying in contact but being susceptible of relative nutation during passage of thread therebetween and through the aperture beside said stem, and a cage for confining said disk, said cage comprising a sleeve-like portion movable axially of said thread opening to maximum and minimum predetermined positions and adapted when in the minimum position to permit the disk to exert its nutational tension-exerting movement and having an uninterrupted circular opening of sufficient diameter to permit tilting and partial emergence of said disk from said cage when said cage is in maximum position but of insufficient diameter to permit complete removal thereof, the opening in said cage permitting unhindered approach of the thread to said disk throughout an arc of 360° and the maximum vertical movement of said cage being limited to prevent turning over of said disk, the space defined by said cage when in maximum position and the contour of said disk being adapted to insure return of said disk to normal operating position upon return of said cage to its minimum position.

4. In a twisting spindle of the type wherein a tension-exerting body constituted as a disk and having a downwardly directed stem reposes on a surface in said spindle with the stem extending loosely into an axial opening in said spindle through which thread passes and wherein said disk performs a nutational movement while exerting tension on said thread, the improvement that comprises: providing a sleeve-like cage about said disk having an uninterrupted circular opening of less diameter than said disk and movable axially of said thread opening to maximum and minimum predetermined positions and adapted when in the minimum position to permit the disk to exert its nutational tension-exerting movement and adapted when in the maximum position to permit partial emergence of said disk through the opening in said cage sufficiently to permit passage of a threading-up tool through said opening and past said disk, said opening being of insufficient diameter to permit complete removal of said disk from said cage and the maximum vertical movement of said cage being limited to prevent turning over of said disk in said cage, the space defined by said cage when in maximum position and the contour of said disk being such as to cause said disk automatically to resume its normal operating position upon removal of said threading-up tool, the opening in said cage being disposed to permit unhindered approach of the thread to said disk throughout an arc of 360°.

5. In a twisting spindle of the type wherein a round tension-exerting body constituted as a disk and having a downwardly directed stem reposes on a flat surface in said spindle with the stem extending loosely into an axial opening in said spindle through which the thread passes and wherein said disk performs a nutational movement while exerting tension on said thread, the improvement that comprises: providing a sleeve-like cage about said disk having an uninterrupted circular opening of less diameter than said disk and movable axially of said thread opening to maximum and minimum predetermined positions and adapted when in the minimum position to permit the disk to exert its nutational tension-exerting movement and adapted when in the maximum position to permit partial emergence of said disk through the opening in said cage sufficiently to permit passage of a threading-up tool through said opening and past said disk, said opening being of insufficient diameter to permit complete removal of said disk from said cage and the maximum vertical movement of said cage being limited to prevent turning over of said disk in said cage, the opening in said cage being disposed to permit unhindered approach of the thread to said disk throughout an arc of 360°.

6. In a twisting spindle of the type wherein a round tension-exerting body constituted as a disk and having a downwardly directed stem reposes on a flat surface in said spindle with the stem extending loosely into an axial opening in said spindle through which thread passes and wherein said disk performs a nutational movement while exerting tension on said thread, the improvement that comprises: providing a confining cage about said disk adapted to permit the nutational tension-exerting action of said disk and raising of said disk from its position of repose on said spindle to a position permitting passage of a threading-up tool through said opening but preventing complete removal of said disk from said spindle and the turning over of said disk within said cage, said cage having an uninterrupted circular opening permitting unhindered approach of the thread to said disk throughout an arc of 360°.
